UNITED STATES PATENT OFFICE.

LOUIS O. FRENCH, OF MILWAUKEE, WISCONSIN.

FUEL-INJECTION SYSTEM.

Application filed April 21, 1926. Serial No. 103,561.

The invention relates to fuel injection systems, and more particularly to electrically-controlled fuel injection systems for internal combustion engines.

5 One object of the invention is to provide certain circuit arrangements wherein an engine-controlled variable resistance serves as the timer and control means for the operating electromagnet of an electrically-controlled fuel-metering device associated with the injection system of the engine.

A further object of the invention is to provide a fuel injection system wherein the control is effected through the operation of a 15 primary circuit and the fuel-metering device is in a secondary circuit, preferably of higher voltage, said primary circuit also including a variable resistance to vary the action of the fuel-metering device so as to vary the amount 20 of fuel charges injected into the engine.

A further object of the invention is to associate the resistance timer and control means with a low voltage timing-and-energizing circuit by which current of higher 25 voltage is induced in a secondary circuit containing the operating electromagnet of the electrically-controlled fuel-metering device. With such a system some current is flowing in the primary winding of the induction coil 30 at all times, and the cutting out of resistance enables this current to build up rapidly at the desired time and thus improve the inductive effect of the secondary winding which, because of its higher voltage, produces a quick action of the operating magnet 35 of the metering device at the desired time.

The invention further consists in the several features hereinafter set forth and more particularly defined by claims at the conclusion hereof.

Fig. 1 is a view showing a system embodying the invention.

Fig. 2 is a detail sectional view of a fuel-metering device for use in the system;

45 Fig. 3 is a modified form of the system shown in Fig. 1.

In Fig. 1, the timing control means is an engine-controlled variable resistance 5, which is more particularly shown and described in my application Serial No. 170,328, filed Feb. 23, 1927, being a continuation in part of my application Serial No. 99,325, filed April 2, 1926, and is preferably of the

pressure type wherein the resistance material, either in disk or powdered form, is mounted in a casing 6 of insulating material and is acted upon by a thrust member 7 which may be moved directly by a timing cam 8 but preferably through a lever 9 interposed between said cam and the insulated head 10 of the member 7, a spring 11 serving to hold said lever in engagement with said cam. The lever 9 is pivotally mounted at 12 upon a support 13 rotatable relative to said cam to advance or retard the time of cutting out of resistance, as shown in said application, and the cam 8 is preferably slidably mounted on a shaft 15, either driven by the engine or rotated in cyclic synchronism therewith. The casing 6 is secured to 70 posts 16 on the support 13 by bolts 17 which are insulated from said posts.

The electromagnetically-controlled fuel-metering device may be of any suitable form and in Fig. 1 I have shown it as a fuel-control valve. This valve is herein shown, for the purpose of illustration, as a fuel injector valve 18 mounted in the engine cylinder 32, but the present invention is not limited to this arrangement, as fuel regulation or 80 metering may be obtained by having the electromagnetically-operated valve function as a suction or by-pass valve of a pump or as a valve in the discharge line of the pump associated with a fuel injector valve. The electromagnetically-operated fuel-metering-and-control valve may be of any suitable construction and as an example of one form reference is here made to my co-pending application Serial No. 84,102, filed Jan. 27, 90 1926.

The metering device shown in Fig. 2 is one wherein the electromagnet operates the expressing member 33 of a fuel pump 34, and due to the varying of the current passing through said operating magnet varies the amount of fuel supplied to the fuel injector (not shown) associated with the engine cylinder. The pump 34 has a suction valve 36 urged to its seat by a spring 37 and a discharge valve 38 urged to its seat by a spring 39, the pump receiving fuel through a pipe 40 connected with a supply tank or priming pump and discharging it through the pipe 41 connected to the fuel injector. 100 The member 33 is connected to a solenoid 105

plunger 42 working in the non-magnetic spool 43 surrounded by a suitably insulated energizing coil 44. The solenoid is preferably of the iron-clad type including a shell 5 or partial shell 45 of magnetic material associated with a stop 46 of similar material. The plunger 42 works in a bore in the stop 26 and the face of this stop and the adjacent end of the plunger are preferably concave 10 shaped so as to increase the magnetic effect of the solenoid as much as possible by decreasing the air gap between these parts for a relatively long movement of the plunger 42. A shoulder 33' is provided on the non-magnetic plunger so as to just prevent contact between said plunger and said stop when said plunger is at the end of its expressing stroke and thus prevent the possibility of freezing. The plungers 33 and 20 42 are moved on their expressing stroke by the energization of the solenoid and on their suction stroke by a spring 47 interposed between a shoulder 48 on the plunger and the shell 45, and an adjustable stop 25 screw 49 mounted in a fixed support 50 limiting the outward movement of said plungers.

In the arrangement shown in Fig. 1, the resistance timer 5 is included in a primary control circuit and the operating magnet for 30 the metering device in a secondary circuit. The primary circuit includes a battery 62 grounded at one side at 63 and connected by a conductor 64 to one terminal of the primary winding 65 of an induction coil 66, the 35 other terminal of said winding being connected by a conductor 67 with one terminal of the timer 5 whose other terminal is grounded at 68. A manually-operated cut-out switch 62' is provided in the conductor 40 64. The secondary circuit includes the secondary winding 69 of the induction coil, grounded at 70 and connected by a conductor 71 with the driven brush 72 of the distributor 73, a variable resistance 74 being shown 45 associated with the conductor 71, though such resistance may be included in the primary circuit and in each case modify the effect of the timer resistance. The distributor brush 72 cooperates with contacts 75 to 50 respectively distribute the current to the metering devices by conductor 60, as in the first construction, said devices being grounded at 61. The brush 72 may ride on the contacts 75 which are preferably of a length 55 to provide contact with said brush during the period of low current flow in the primary circuit, or said brush may be spaced a slight distance from said contacts so that where high tension current is used in the 60 secondary circuit such current will jump the small air gap to complete the circuit through the metering device.

With this construction the cam 8 periodically acts to cut out resistance from the 65 primary circuit and at such a time as it is

desired to have the metering device function, and thereupon, due to the rapid change in voltage, current is induced in the secondary circuit and preferably of a higher voltage, and while the brush 72 is operatively associated with one of the contacts 75 and under these conditions current flows through the control magnet of the metering device to cause its operation. While but a single control has been provided in the 75 primary circuit for controlling all the metering devices, it will, of course, be understood that a separate resistance and induction coil may be associated with each metering device without departing from the broad 80 concept of the invention.

In either arrangement the timing cam 8 may have rotary motion alone so that as the speed of the engine increases the time during which resistance is cut out to permit the 85 metering device to operate decreases, but I prefer to provide a greater range of adjustment of the timing period and/or the amount of resistance periodically cut out of the control circuit by providing a cam 90 of varying contour, such as those shown and described in said application Serial No. 99,325, it being noted that where the metering device is a control valve associated with the supply side of the pump the period during 95 which the valve is held open is the prime factor and that the varying of the amount of resistance cut out produces a variable lift of the valve 26 or a variable stroke of the member 33, and is more particularly of advantage where the control valve 26 is used in the discharge line of the pump or the plunger of the pump is electrically operated. The varying of the position of the cam and its automatic advance 100 or retard under governor action being more particularly shown and described in the aforementioned application, it has not been shown here but may, of course, be used in this system.

In the arrangement shown in Fig. 3 the primary circuit includes a battery 78 connected by a conductor 79 to contact 80 of switch mechanism 80', suitably insulated from a supporting casing 81 and cooperating with contact 82 pivoted at 83 to the casing 81 and grounded at 84, and the other side of the battery is connected by conductor 85 to brush 86 bearing on a switch arm 87 of a variable resistance 88 and engaging 115 the resistance element 89 connected by conductor 90 with the primary winding 91 of an induction coil 92, which winding is grounded at 93, thus completing the primary circuit when the contacts 80 and 82 120 are engaged. The secondary circuit includes the secondary winding 94, grounded at 95 and connected by conductor 96 to the rotating distributor brush 97 operatively associated with contacts 98 of the distributor, 125 130

each of said contacts being respectively connected by a conductor 100 to the energizing coil of one of the metering devices 18 (only one being shown), the other side of 5 said coil being grounded at 101, thus completing the circuit through the secondary winding at a time when the brush 97 and one of the contacts 98 are in cooperative position.

10 The switch mechanism 80' may be of any suitable construction but preferably it includes a timing cam 102 slidably mounted on a shaft 103 driven by the engine, and a spring 104 moves a part 105 on said contact 82 against said cam and when the relief 15 106 moves past said part the spring 104 moves the contact 82 into engagement with the fixed contact 80.

15 The casing 81 may be turned relative to 20 the cam 102 to advance or retard the time of operation, and for a more detailed showing of switch mechanism useable in this system reference may be had to my copending application Serial No. 26,676, filed Apr. 25 29, 1925, and Serial No. 88,406, filed Feb. 15, 1926.

20 The switch arm 87 may be manually or governor-operated and as here shown is 30 suitably insulated from its shaft 107, pivoted on a fixed support 108, and from an arm 109 connected with said shaft and having a forked end with suitable projections engaging in the annular groove of collar 110 of a governor 111 mounted on a shaft 35 112 driven by the engine. A more detailed showing of the variable resistance associated with a governor will be found in my copending application Serial No. 88,406, previously mentioned.

40 In the arrangement shown in Fig. 3, during the time the primary circuit is closed and the brush 97 is passing over one of the contacts 98 current will flow in the secondary circuit and energize the operating magnet of the metering device associated with this contact, and by varying the position of the switch arm 87 the strength of primary current will be varied and hence the secondary current will be varied, and hence the 45 50 action of the operating magnet will be varied and thus varying amounts of fuel charges will be delivered to the engine cylinder.

55 Thus, where the metering device is a control valve in the discharge line of the fuel pump or is the plunger of the pump, varying the resistance will vary the lift of said valve or the stroke of said pump to vary the amount of fuel supplied to the engine, and where the resistance is controlled by a 60 speed-responsive device, such as the governor 111, the resistance may vary with the speed of the engine or effect a gradual reduction of fuel charge as the speed increases, 65 or said resistance may be maintained con-

stant through a predetermined speed range and then through governor action vary above said speed until in either case when a predetermined maximum speed is reached the resistance then included in the circuit 70 is so great that not enough current will be induced in the secondary circuit when the contacts 80 and 82 are engaged to cause the operating magnet of the metering device to lift the valve or move the pump plunger, and 75 hence the supply of fuel to the engine is interrupted until the speed drops below the predetermined maximum.

I desire it to be understood that this invention is not to be limited to any particular form or arrangement of parts except in so far as such limitations are specified in the claims or necessitated by the prior art.

What I claim as my invention is:

1. In a fuel injection system for internal 85 combustion engines, the combination of a primary control circuit including a variable resistance, a secondary circuit inductively associated with said primary circuit and periodically influenced thereby in cyclic synchronism with the engine, an electromagnetically controlled fuel-metering device controlling the amount of fuel delivered to the engine and having its control electromagnet included in said secondary circuit, and 90 means for varying said resistance to vary the action of said control electromagnet and thus cause said metering device to vary the amount of fuel charges delivered to the 95 engine. 100

2. In a fuel injection system, the combination of a primary control circuit including a variable resistance, engine-controlled means for periodically varying said resistance, and an electromagnetically-controlled 105 fuel-metering device having its control electromagnet inductively associated with said primary circuit and controlled thereby.

3. In a fuel injection system, the combination with a closed primary circuit including 110 a variable resistance, engine-controlled means for periodically varying said resistance, and an electromagnetically-controlled fuel-metering device having its control electromagnet inductively associated with said primary circuit and controlled thereby. 115

4. In a fuel injection system, the combination with a primary control circuit including a variable resistance, a variable engine-controlled means for periodically varying said 120 resistance, and an electromagnetically-controlled fuel-metering device having its control electromagnet inductively associated with said primary circuit and controlled thereby. 125

5. In a fuel injection system, the combination with a primary circuit, means for periodically varying the intensity of current in said circuit, a secondary circuit inductively associated with said primary circuit, and a 130

fuel-metering device having a control electromagnet in said secondary circuit influenced by said primary circuit to operate said metering device on the periodic increase of current in the primary circuit.

6. In a fuel injection system, the combination with a primary circuit, means for periodically varying the intensity of current in said circuit, a secondary circuit inductively associated with said primary circuit, a fuel-

metering device having a control electromagnet in said secondary circuit and influenced by said primary circuit to operate said metering device on the periodic increase of circuit in the primary circuit, and means for varying the amount of periodic increase of the current.

In testimony whereof, I affix my signature.

LOUIS O. FRENCH.
